UNITED STATES PATENT OFFICE.

J. THEODORE GURNEY, OF BOSTON, MASSACHUSETTS.

TWO-WHEELED VEHICLE.

SPECIFICATION forming part of Letters Patent No. 361,940, dated April 26, 1887.

Application filed May 27, 1884. Serial No. 132,923. (No model.)

To all whom it may concern:

Be it known that I, J. THEODORE GURNEY, a citizen of the United States, residing at Boston, in the county of Suffolk and State of Massachusetts, have invented certain new and useful Improvements in Vehicles, of which the following is a specification, reference being had therein to the accompanying drawings.

Figure 1 is a side elevation of a vehicle embodying my improvements, a portion thereof being broken away. Fig. 2 is a side view of one of the supporting-brackets for the driver's seat. Fig. 3 is a cross-section on the line x_1x_1 , Fig. 1. Fig. 4 is a section on the line y_1y_1 , Fig. 1. Fig. 5 shows in perspective the skeleton frame on the body. Fig. 6 is a cross-section of the body on the line z_1z_1 , Fig. 1. Fig. 7 is an outside front view of the lower part of the front wall of the body. Fig. 8 is a section on an enlarged scale on the line x_2x_2 , Fig. 1. Fig. 9 is a section of the parts similar to those in Fig. 8, though slightly modified. Fig. 10 is a rear view of the vehicle. Fig. 11 is a cross-section on the line x_3x_3 , Fig. 10. Fig. 12 is a section on the line y_2y_2 , Fig. 10.

In the drawings, A represents, generally, the body of the vehicle; B B, the wheels upon which it is mounted. The wheels are secured to a crank-axle having the horizontal wheel-arms D D, the downwardly-depending parts D', and the drooping portion D'', the parts D D' forming what I term the "axle-wrists."

E E represent, generally, the side springs. Each of these consists of several plates or leaves, arranged in substantially the ordinary manner, the springs being secured to the under sides of the wheel-arms D D. The rear end of the under plate, e, of side spring is formed with upwardly-extending ears e', which are placed close to the sides or edges of the upper plates or leaves, the purpose being to prevent any displacement of the leaves relatively to each other. Ears of this character hold the plates firmly in position, and by forming them upon the end of the lower plate a simple but effective clamping device is provided. The rear end of the top plate, e'', is also provided with plates or ears extending downwardly, as shown at e'', and between these lie the end or ends of one or more of the lower plates. They are specially adapted to hold securely in place the long second leaf next to the top, and when

this clamp is employed the ends of the spring-plates are held rigidly together.

Vehicles of the character which I have shown are specially liable to have the springs twisted so as to force the spring plates or leaves apart; but by the use of the simple devices which I have shown I effectually prevent this and preserve the springs for a long time in a solid condition; but springs of any of the known forms can be used.

At the front ends of side springs are secured two hangers or bracket-arms, E. These latter are firmly bolted to the front lower corners of the body, and project forwardly and outwardly somewhat, sufficiently far to properly support the forward ends of the springs. Other means of supporting the front ends of these springs can be employed instead of that above described; but the best results are attained by having the side springs extend to points in front of the body, as a prolonged spring-support can be thereby provided, and the entrance being in the rear, the projecting springs do not impede the doorway, as the rear ends of the side springs stop in front of the rear wall.

The rear ends of the side springs are connected by means of the cross-spring F, which is preferably of the character shown in Fig. 10, this figure showing also the preferred means of attaching it to the body.

F' is a metal plate lying beneath the center of spring F, supported from the bottom of the body by means of rods F'', bolted to the body. Preferably there are two of these hangers F'' on each side of the center and two on each side of the spring. This rear cross-spring serves two purposes among others. It not only provides a resilient support for the body, but also provides a means for supporting the rear ends of the side springs and for connecting them to the body. Upon the running-gear thus provided I suspend the body, the parts of which are constructed and arranged as follows:

In Fig. 5 I have shown a frame-work adapted to support the body proper, this frame-work having at the rear corner uprights G G, at the front corners uprights G', together with uprights G'' by the sides of the door, intermediate uprights, G³ G³, in the front wall, bottom sills, g, top sills, g', sills g'' at the bottoms of the windows, sills g³ at the bottoms of the side portions, brackets g⁴ and ribs g⁵ at the top. Upon

the frame-work thus provided I support the external sheathing. This, for some purposes, I prefer to be of sheet metal, but do not herein make claim thereto, having presented that as the subject-matter of another application. So far as the purposes of the present case are concerned, use may be made of any preferred material in constructing the body.

The window-sashes may be constructed originally in substantially the ordinary way, I representing the glass, and I' the bottom piece of the frame. The sill, instead of receiving the window upon a square surface, as customary, carries an upwardly-extending edge, 15 which fits into a groove in the bottom of the bar I'. This upwardly-extending edge is shown as being provided by a bar or plate, I², secured to the sill g²; but I do not wish to be limited to exactly that form. As shown, it is 20 secured by screws and its upper edge beveled, the groove in the bar I' being correspondingly beveled or V-shaped. When the opposing parts are thus shaped there will be a guarantee that the bar I' shall always fit tightly upon the part I², as will be readily understood. In 25 a cab or vehicle constructed in this way the rattling of the windows is entirely overcome; and this has been a great annoyance to those riding in these vehicles. I do not wish to be limited to exactly the form shown in Fig. 8, 30 as many of the advantages incident to this part of the structure can be obtained by devices of the style shown in Fig. 9.

J represents the door. It consists of a single part supported upon hinges at one side, as 35 at j, the fastening device j' being upon the opposite side, the hinges engaging with one of the fixed walls of the body and the fastening device with the opposite wall. The shape of 40 the door in cross-section through the window portion is shown in Fig. 11.

Heretofore the doors that have been used in the rear of vehicles have been made in two parts, one swinging to one side and the other 45 to the other side. This also has been found a matter of great annoyance, and I have devised a door which, as said, is constructed of a single part curved in horizontal section, whereby I obviate the necessity of opening and shutting 50 two or more parts, and at the same time preserve the expanded interior space due to the outward curve of the door and open a field for novel designs in vehicles of this class. In the upper part of the door windows are formed, 55 these having plates of glass J'. By examining these it will be seen that they are not curved, as are those jointly used in carriage windows or doors, but are flat, the recesses in the sides being cut to correspond to their shape. As 60 the door consists of a single part, these window-panes may be quite wide, and yet have sufficient support by means of the intermediate upright, J². When two doors are used, the uprights, to be sufficiently strong, take up much 65 of the room, which I can make available for the window-panes. The flat panes of glass are much cheaper than the curved ones which

have been heretofore used, and as they are being constantly broken in vehicles of this character, it is a matter of considerable importance to be able to replace them with ordinary panes of glass. The expense of repairing the door or window is much less since I have devised this combination with the curved door of the flat panes.

The lower portion of the door is constructed in the manner indicated in section in Fig. 12—that is to say, the upright pieces J³ support two curved sheet-metal panels, H⁸ and H⁹, one upon the inside and one upon the outside. By 70 employing a panel upon the inside a support is furnished for a cloth covering; or it may be made the basis of an ornamentation by paint and varnish.

The driver's support comprises the seat 85 proper, K, and the foot-rest K⁷, both being in front of the axle. As will be described below, the shafts are secured flexibly to the vehicle independently of this driver's support.

K' K² K³ K⁴ K⁵ represent the parts of one of 90 the metallic brackets or holders for the driver's support, these projecting forward from the body. The parts K³ K⁴ extend far enough to carry the foot-rest, they being preferably at the sides of the latter.

K⁶ is an upwardly and outwardly extending supplemental brace, preferably curved and fastened to the foot-rest and seat-support. When the shafts are attached as herein provided for, the driver's foot-rest and seat can 100 be made light and open, so as to leave an unobstructed space between the foot-rest and the body, wherein, if desired, can be stored such articles as are needed in using these cabs, and, moreover, these parts can be made ornamental 105 and pleasing in design.

The draft devices in the construction shown in Fig. 1 consist of the shafts L, joined together by a cross-bar, L', and, if desired, by a spring at L², though the latter is not essential.

L³ are springs secured to the rear ends of the shafts and extending backwardly therefrom to the body, they passing into the body, to which also they are directly connected. Preferably they are carried back to a point sufficiently 115 behind the front wall, and may be secured either to the inside or the outside of the framework. As shown, they are passed through apertures (see Fig. 7) and are fastened to sills or frame-pieces, as shown in Fig. 1. At the front ends the springs are rigidly secured to the shafts by means of bolts l⁷ l⁸, supplemented by a clamp or clip, l'. These springs operate to relieve the body of the motions which are ordinarily imparted thereto from the horses, and it is left to float substantially free without vertical oscillation or rocking. It will be seen, of course, that there are many ways in which these springs, secured at the rear ends of the shaft, can be joined to the body; but the best results will be obtained by locating them at points above the axle and joining them to the wider portions of the body. It is not necessary that they should be joined to the very

widest parts above the seats, as they can be located at a short distance below the seats and attain the end aimed at.

In other applications, Nos. 132,922 and 5 72,548, (renewed as 206,534,) I have shown modifications of the flexible shaft-connection at the rear end, said fastening consisting of a hinge united directly to the frame of the body.

I am aware of the English patent to Poole, 10 No. 7,188 of 1836, and of the French patent to Fabas, No. 6,033, of 1838, and do not claim as my invention the features of arrangement and construction therein shown. In these the driver's seat extends to points back of the axle, 15 the shaft runs to the body on lines above the passengers' seats and above the greatest weight in the interior, and the harness-traces are themselves connected to the body. In my construction I utilize the shafts to apply the draft, 20 and hinge them near the plane of the passengers' seats, (preferably at or a little below the seat,) and as a result I can carry the driver's seat lower down and farther forward, and can cause his weight to balance that of the passengers; 25 and, moreover, I can prolong the body backward, so as to increase the capacity of the vehicle.

Q represents a band or strip of iron which is passed around the body, it being preferably 30 situated on a line somewhat below the windows. Preferably, it is made of a strip long enough to pass entirely around the cab, or at least from one edge of the door around to the other edge, and after being secured in position 35 it acts to clamp the outer parts to the inner frame, and also clamps the parts of the frame firmly together. Moreover, it tends to enhance the pleasing effect on the eye.

R represents the bell situated below the 40 driver's seat, by means of which the passenger can signal to the driver. It may be of the usual style of gong-bells. There is a rod extending backward and through the front wall of the cab, and to it is attached a knob, as 45 shown in Fig. 6.

Having above described a particular form of vehicle embodying my invention, I wish it to be understood that in several respects there can be more or less variation without departing 50 from the spirit thereof, such variations being well known in the art prior to the date of this patent.

I herein speak of the axle as being "cranked," thereby meaning that it is bent so as to take 55 the central part thereof away from proximity to the bottom of the body, and is formed to have wrists with wheel-arms at the ends. The central bent or cranked part of the axle is carried away from the bottom of the body, so that 60 the latter can (when pressing on the springs) fall below the wheel-axis, and so that the body as a whole can be brought lower than if the axle were straight from wheel to wheel. I do not claim, broadly, of course, to be the in- 65 ventor of such an axle, as I am aware that they have been used in various forms, the cranked part having been sometimes dropped

directly down, as in the French patent to Fabas, No. 6,033, August 30, 1838, and sometimes having been turned in front of the body, as 70 shown in Patent No. 1,789, to J. Page, September 14, 1840, both of these forms of axle being equivalent so far as concerns the matter referred to. I prefer to drop the cranked part down; but some of the features of my invention 75 can be preserved if the axle be arranged as in the said patent to Page.

I am also aware that shafts for sulkies and other vehicles with open bodies, (and with the entrance-way in front of the wheels,) and without a seat or support specially intended for the driver in front of the axle, have had springs combined therewith in various ways to obtain an advantageous shaft-connection; but I am not aware of the fact that prior to my invention vehicles of the class to which my invention relates had been constructed with the features which I have devised, and by which I not only have succeeded in making such cabs much more durable than heretofore, but also have 85 overcome the great objections which for many years previous were incident thereto and which prevented them from being successfully used extensively for passenger traffic. When the parts are arranged as I have shown, 90 it will be seen that the greater portion of the cab-body lies in rear of the wheel-axis, and it will also be seen that the shafts or draft devices are secured to the body behind or below and independently of the driver's support. 95 Heretofore in vehicles at all resembling mine the shafts were fastened to a frame-work projected from the body-frame forward to hold the driver's support, as is illustrated in the patent to P. Herdic, No. 259,310, June 13, 100 1882. When the draft devices are thus united to the driver's support or its projecting frame, the said support and frame must necessarily be made much heavier and stronger, and even when made in the best way known this part 105 of the vehicle is liable to wear and fracture from the leverage on it, resulting from having the shafts attached thereto.

By examining Fig. 5 it will be seen that I do not project any of the body-sills or frame-bars in front to carry the driver's support; and as I dispense with this way of uniting the shafts and join them to the parts drawn thereby at points behind or below the driver's support, I am enabled to not only secure a better 110 balancing of the body around the wheel-axis, but can do away with much of what has been heretofore necessary as a driver's support and can make the latter lighter and more open and can place the driver's seat in a higher position 115 relatively to the other parts. In another respect my construction differs materially from those illustrated in the last said Herdic patent—namely, in this, that I secure the side springs not to the bottom or bent drooping 120 central part of the axle, but to the axle-wrists D D', and therefore near the plane in which the draft is applied, the fastening of the springs 125 being effected near the wheel-axis. This ena-

bles me to apply the spring with much better effect and to use a simpler form of spring, also to use a simpler form of spring-support and to bring the body into a more desirable position.

5 While I have shown and for most purposes prefer that the flexible connection for the rear end of the shafts should be of the nature of a flat metallic extension-spring, yet some of the 10 ends at which I aim can be attained if other forms of flexible connection be used—such as the hinge which I have shown in application Nos. 72,548 (renewed as 206,534) and 132,922—provided said connection be united directly to the cab body or frame behind or below the 15 driver's support or its frame. In fact, some of the desirable features of my arrangement and construction of the parts are independent of the shaft-connection, and can be preserved 20 even when the shafts are attached in the way shown in the aforesaid Page patent; but in such case the body should be balanced in the manner I follow, and there should be a spring employed below the driver's support to hold the 25 front part of the body.

I herein refer to a spring or springs as "interposed between the shaft and the parts drawn thereby," and wish to be understood as meaning that these springs are so arranged as to 30 relieve the body of horse motion, whether they are interposed directly between the body and the shafts or indirectly through the medium of other parts, so long as the combination and arrangement I have invented be preserved.

35 In open sulkies with bodies elevated above the shaft-line and with the driver's seat directly over the axle, springs have been interposed both directly and indirectly, to produce combinations and arrangements different from 40 that at which I aim, as shown in the patents to Baillau, No. 18,077, November 1, 1857, and Thomas, No. 249,730, November 15, 1881, and in some of these open sulkies with elevated bodies and front entrances shafts have been 45 used which were hinged at the front corner and terminated in pivotally-attached springs at the rear corner, as shown in the French patent to Bedel, No. 96,917, October 8, 1872, and at the date of this present patent it is well 50 known that shafts of this character can be substituted in the combination of parts which I have invented for these cabs instead of the specific form of shaft which I herein show.

55 Another matter of advantage incident to my construction is that the shafts are not at their rear ends spread apart so as to lie outside of the outer vertical planes of the upper part of the body, although they are outside of the vertical planes of the bottom. The body, like 60 that of some earlier cabs, has a lower narrower portion and an upper wider portion, the seats being at the bottom of the latter and above the narrower portion.

The fastening devices of the shafts are in or 65 near the horizontal planes of the passengers' seats, (preferably below)—that is to say, in or below the horizontal planes of the greatest in-

terior weight when the cab is loaded—in order to apply the draft to the best advantage. When springs like those shown at L³ are used, rigidly fastened at one end to the body and at the other end to the shaft, they perform two functions—namely, first, allow an axial motion of the shafts relatively to the body, and, second, provide resilience—and in this respect said 75 springs L³ take the place of a hinge in conjunction with a rearwardly-extending spring attached loosely to the body.

As shown, the parts which immediately fasten the rear ends of the shafts to the body lie inside of the wall; but they may be put at any of the well-known equivalent places. By having the larger part of the body in rear of the wheel-axis, and having more or less of the driver's support project forward from the 85 closed front wall, (the passengers being permitted to enter and pass out through a rear door,) I can preserve a uniform balance around the said wheel-axis. By means of flexible connections for the shafts in the above-described 90 planes relative to the interior weight, I can prevent this balance from being seriously disturbed, and by securing these flexible connections directly to the body, independently of the driver's support, I can make the vehicle 95 much lighter, though more durable.

I am aware of the fact that heretofore cabs have been constructed with the driver's support (including the seat and the foot-rest) partly in rear of the front wall of the cab, as 100 shown in the aforesaid Page patent; and although I prefer to have this support arranged as herein shown, yet it can be made more or less similar to that shown in the said patent if there be a sufficient part of it projecting forward to insure a proper balancing of that part of the cab which lies behind the wheel-axis.

105 Although some of the matters herein claimed are illustrated, also, in my aforesaid applications, Nos. 132,922 and 72,548, (renewed as 206,534,) I do not claim the said matters therein, nor do I herein claim any of the combinations set forth in the claims appearing in the other said applications, respectively, or in the claims in my Patent No. 272,238, February 13, 1883. 115

What I claim is—

1. In a two-wheeled cab, the combination of a cranked axle, the body having passengers' seats transverse to the axle, with a door in the rear and a closed front wall, the driver's seat in front of the axle, the side springs secured to the axle-wrists, a shaft having its rear end flexibly connected to the vehicle in or below the planes of the passengers' seats, and a spring interposed between the shaft and the parts drawn thereby at a point in front of the flexible connection which unites the rear end of the shaft to the vehicle, substantially as set forth.

2. In a two-wheeled cab, the combination of the cranked axle, the body having passengers' seats transverse to the axle, with a rear door, and the driver's seat in front of the axle, the side springs secured to the axle-wrists, a shaft,

- a spring directly connecting the shafts flexibly with the body, and an auxiliary spring for the shaft interposed between it and the parts drawn thereby, substantially as set forth.
5. In a two-wheeled cab, the combination of the cranked axle, the body having a rear door and a closed front wall, the driver's support in front of the axle, the side springs secured to the axle-wrists, a shaft, and two springs (additional to the side springs) at different points longitudinally of the shaft, one spring being a rearward extension of the shaft, and both being directly attached to the shaft and interposed between it and the parts drawn thereby, substantially as set forth.
10. In a two-wheeled cab, the combination of the cranked axle, the body constructed substantially as described, the side springs secured to the axle-wrists above the cranked part D² of the axle, the flexibly-connected shaft, the support projecting forward from the body to carry the front ends of the side springs, and supports for the rear ends of the side springs, uniting them with the body, substantially as set forth.
15. In a two-wheeled cab, the combination of the cranked axle, the body and driver's support constructed and arranged substantially as set forth, the side springs for the body connected to the axle-wrists above the cranked part D² of the axle, the flexibly-connected shaft, the rear cross-spring, and supports which carry the front ends of the side springs at points in front of the body, substantially as set forth.
20. In a two-wheeled cab, the combination of the cranked axle, the body having a rear door and having its greater portion in rear of the wheel-axis, the driver's support in front of the axle, the side springs secured to the axle-wrists above the cranked part D² of the axle, the shafts flexibly connected to the parts drawn thereby independently of the driver's support, and a spring interposed directly beneath the driver's support and the shaft, substantially as set forth.
25. In a two-wheeled cab, the combination of the axle having the cranked portion and wrists, the body having the narrower lower part between the wrists and an upper wider part for the seats, the semi-elliptic side springs, the shafts having their rear ends on a line above the bottom and immediately below the wider parts of the body, and the springs projecting back from the shafts and joined directly to the body, the fastening devices for the rear ends of the springs being behind the front end of the body, substantially as set forth.
30. The combination, with the shafts and the cab-body closed at the side and front, of the metallic shaft-springs rigidly fastened to the shafts, and also rigidly fastened directly to the body, substantially as set forth.
35. The combination, with the shafts and the cab-body closed at the sides and front, of the metallic springs fastened to the shafts and inserted through the front wall of the cab-body, substantially as set forth.
40. The combination, in a two-wheeled vehicle, of the body, the springs which support the body, the shafts having their rear ends on lines above the bottom of the body, and flat metallic springs extending back from the shafts and uniting them directly to the body in or near the horizontal planes of the seats, substantially as set forth.
45. In a vehicle, the combination of the movable window provided with a bar having a groove in the bottom and a supporting or retaining bar secured to the window-casing, and provided with an edge adapted to enter the aforesaid groove, substantially as set forth.
50. In a two-wheeled vehicle of the character described, the combination, with the vehicle-body, of the door which is situated at the rear side of the body and consists of a single part extending from side to side of the doorway, the upright or uprights J², and two or more flat panes of glass supported in the window portion of the doorway, substantially as set forth.
55. In a two-wheeled cab, the combination of the body having a closed front wall, the shafts flexibly connected to the parts drawn thereby below and independently of the driver's support, and the metallic brackets secured to the front wall and extended outward at the sides of the driver's foot-rest to support it, substantially as set forth.
60. In a two-wheeled cab, the combination of the body, the shafts secured to the parts drawn thereby independently of the driver's support, the metallic brackets secured to the front wall and projecting outwardly to support the driver's foot-rest, substantially as set forth, to leave an open space between said foot-rest and the front of the cab, and a spring below the foot-rest, substantially as set forth.
65. In a two-wheeled cab, the combination of the body having a closed front wall, the shafts having their rear ends on a line above the bottom and immediately below the wider parts of the body, and the springs projecting back from the shafts and joined directly to the body, the fastening devices for the rear ends of the springs being behind the front end of the body, substantially as set forth.
70. The combination, in a two-wheeled vehicle, of the body, the springs which support the body, the shafts having their rear ends on lines above the bottom of the body, and flat metallic springs extending back from the shafts and uniting them directly to the body in or near the horizontal planes of the seats, substantially as set forth.
75. In a vehicle, the combination of the movable window provided with a bar having a groove in the bottom and a supporting or retaining bar secured to the window-casing, and provided with an edge adapted to enter the aforesaid groove, substantially as set forth.
80. In a two-wheeled vehicle of the character described, the combination, with the vehicle-body, of the door which is situated at the rear side of the body and consists of a single part extending from side to side of the doorway, the upright or uprights J², and two or more flat panes of glass supported in the window portion of the doorway, substantially as set forth.
85. In a two-wheeled cab, the combination of the body having a closed front wall, the shafts flexibly connected to the parts drawn thereby below and independently of the driver's support, and the metallic brackets secured to the front wall and extended outward at the sides of the driver's foot-rest to support it, substantially as set forth.
90. In a two-wheeled cab, the combination of the body, the shafts secured to the parts drawn thereby independently of the driver's support, the metallic brackets secured to the front wall and projecting outwardly to support the driver's foot-rest, substantially as set forth, to leave an open space between said foot-rest and the front of the cab, and a spring below the foot-rest, substantially as set forth.
95. In a two-wheeled cab, the combination of the body having a closed front wall, the shafts having their rear ends on a line above the bottom and immediately below the wider parts of the body, and the springs projecting back from the shafts and joined directly to the body, the fastening devices for the rear ends of the springs being behind the front end of the body, substantially as set forth.

Witnesses:
J. S. BARKER,
M. P. CALLAN.

J. THEODORE GURNEY.

In testimony whereof I affix my signature in presence of two witnesses.
